UNITED STATES PATENT OFFICE

2,487,896

TOWEL RACK

Jacques Rousso, Los Angeles, Calif.

Application March 26, 1945, Serial No. 584,786

3 Claims. (Cl. 211—16)

1

This invention relates to improvements in towel-holding and towel-locking devices. More particularly, this invention relates to improved means for holding, storing, positioning and controlling towels, both clean and soiled.

More particularly also, the invention relates to the provision of a channeled trackway in which or on which shoes are adapted to move. These shoes are in the form of projections on rings holding one or more towels; preferably a relatively large number of towels.

The invention also relates to improved means for holding towels without cabinets, etc.

The invention also relates to improvements in shelves for positioning and holding towels.

The invention also comprehends improvements in positioning the towel-carrying rings on the rack, so that a set of clean towels will be presented until all the towels are soiled and then these towels may be moved out of the way and replaced by a new set of clean towels.

In general, by the means which I have provided, the rings carrying one or more towels may be positioned in an orderly manner and may be stored and moved into position for use, and moved to the place for storage of soiled towels, all in a consecutive orderly manner.

Another object has been the provision of such a device which is simple to make and use and inexpensive to produce.

Further advantages and objects of my invention will appear and be brought out more fully in the accompanying drawing, in which:

Fig. 1 is a side elevation.

Fig. 2 is a front elevation.

Fig. 3 is a top plan view.

Fig. 4 is a perspective view.

Fig. 5 is a top plan view of one of the rings and its shoe positioned in the trackway of the rack.

Fig. 6 is a side elevation of one of the rings and its shoe in the rack, and illustrating the catch means for positioning a single ring so that one set of the towels is brought in position for use.

Fig. 7 is a detailed section on the line 7—7 of Fig. 4.

Fig. 8 is a view of one type of shoe, and

Fig. 9 is a view of another type of shoe.

Referring to the drawing in detail, in which I have shown the preferred form utilizing the principles of my invention, I have shown a bracket 10 provided with footings 11 and 12. These footings may have openings 13 by which the bracket may be attached to a wall, etc.

Mounted upon this bracket is one end of a channel member or guide 14, which has an upward leg 15 and a top arc 16, and a downward leg 17.

Mounted by welding or otherwise upon the end

2

of the downward leg 17 is an oblong bracket 18, which is preferably welded at the point 19. The bracket 18 has a horizontally extending arm 20 which may be welded to the upward leg 15 at point 21. The bracket 18 is channeled, as at 22, to accommodate the upper end of the bracket 10, to which it may be connected by welding or other means.

A shelf 23 is centrally channeled, as at 24, where it may be welded to the channel member 14 at the top of the arc 16, as particularly shown in Figs. 1, 2 and 3.

The shelf is provided also with fenders 25 for keeping the towels from falling sideways, which shelf may have a lip 26.

The shelf 23 preferably has welded thereto a rod or other similar member 27, which extends through a bore 28 in a second shelf 29, it being understood that the shelf 29 is adapted to pivot on the rod 27.

This second shelf 29 may hang downwardly when not in use upon the rod 27, or it may be swung upwardly so that it will rest also upon a second rod 30, which may be welded, as at 31, to the opposite end of the shelf 23.

Secured to the rod 27 is a spring 32, one end of which is adapted to project in the path of the swinging shelf 29, so as to hold the shelf down, as will be readily understood by those skilled in the art, without further description other than as shown in Fig. 3.

As illustrated in Figs. 1 and 3, also 5 and 6, there is shown a ring 33 adapted to hold a plurality of towels 34. Each ring may be provided with a catch 35 hinged, as at 36, to the balance of the ring. It will be understood, as illustrated in my previous Patent No. 2,363,149, dated November 21, 1944, that locking means may be provided for locking the towels on the rings 33. Each of these rings 33 is provided with a shoe 37 adapted to be engaged in the channel member 14 and to ride therein.

The shoe 37 may be in the form shown particularly in Figs. 5, 6 and 8 or Fig. 9, and is preferably cast or otherwise formed integrally with the ring.

In Figs. 1, 2 and 3 at the lower end of the leg 15 of the channel member 14 I have shown openings 38 for the accommodation of a lock 39, as shown particularly in Fig. 7.

In Figs. 2 and 4 I have shown only one opening 38 in one side of the channel member 14, and this form may be used also, and will satisfactorily prevent the rings 33 from being withdrawn from the channel member 14.

At the upper end of the leg 15 of the channel member 14 I have shown a stationing catch 40, as particularly shown in Figs. 5 and 6, and also in Fig. 1. The catch includes a pivoted member 60 having a leg 41 adapted to normally rest in the

60

pathway of the shoes 37 through an opening 42 in the channel member, and thus normally bar the passage of the shoes.

On the other end of the stationary catch is a weighted member 43, which tends to keep the leg 41 in the path of the shoes.

When it is desired to allow a shoe and the ring with it to pass, all that is necessary is to push the weighted end upwardly and then the leg 41 will be withdrawn from the path of the shoes.

With respect to the operation, to start, the lock 39 may be unlocked by a key in the hands of the operator who presumably will be the laundry employee who picks up the towels. The lock will be withdrawn and in the first instance the shoes 37 of the various rings 33 with the fresh towels will be inserted into the channel member 14 upon the side or leg 15. As many of these rings as will be required will be placed upon the channel member 14 and then these rings will be run up the channel member across the shelf or shelves and down the other leg 17 of the channel member, Fig. 1 illustrating the position of the clean towels on the leg 17. Thereafter the channel member may be locked and the laundry employee may leave with the assurance that the towels will be locked against being stolen.

When it is desired to use these towels, one of the rings will be lifted upwardly on the leg 17, over the top arc 16 of the channel member and with the towels thereon, the shoe passes between the halves of the shelf. The towels may then be allowed to rest on the shelf, as in Fig. 1, or, if it is desired, the auxiliary shelf 29 may also be sprung into position under the towels to further aid in positioning the towels.

It will be understood that the first shoe, when brought over the top of the channel member, will be caught by the catch 40 and will rest there until the catch is operated. When all of the towels on the first ring at the catch are used and it is desired to have new towels from the succeeding ring, the catch may be operated and the shoe 37 of the ring 33 which is caught will travel by gravity down the leg 15 to a point adjacent the lock 39. This operation may be performed over and over with the remaining clean towels until all of the towels are used, or until the laundry man comes, when he will open the lock and remove the rings 33 with the soiled towels 34.

If desired, a second auxiliary shelf 44 may be provided, as shown in Figs. 1 and 2. The shelf may be a pivoted shelf having ears 45 attached upon a pivot 46 through the arm 20 of the bracket 18. At the other end the shelf may rest upon a

spring catch 47 which may be struck out from the bracket 10.

In order to provide for inserting the towels into the rack at the upper end of leg 17, and at the same time provide locking means therefor, I have shown a closure channel member 51, formed in a similar manner to the channel member 14, only somewhat larger, so that the member 51 is adapted to slide up and down on the channel member 14.

The closure member 51 may have an apertured lug 52 integrally or otherwise connected to the back of the closure member 51. Likewise, the back of the leg 17 of the channel member may have integrally or otherwise connected thereto a similar apertured lug 53.

The lugs are adapted to be locked together by a lock 54, having a bolt 55.

The leg 17 is adapted to have a cut-out 50 in the sides thereof, so that the shoes of the ring members may be inserted therein, and thus the towels may be dropped downwardly on the leg 17 of the rack.

Ordinarily the cut-out will be covered by the closure member 51, the closure member being normally locked in place to lock the towels.

When it is desired to take towels off or to insert towels upon the leg 17, the closure member 51 may be unlocked and moved upwardly off the cut-out 50. When the towels have been removed and inserted, then the closure member 51 may be dropped down over the cut-out 50 and locked.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. A rack for holding a plurality of bundles of towels comprising, in combination, a track having a channel therein, a plurality of towel holding rings slidable in said channel, means locking the rings on said track, and means holding a plurality of bundles of clean towels at one end of the track with the said bundles locked on the track.

2. A towel rack of the character described, comprising a track, a channel in said track, a plurality of shoes slidably mounted in the track, a corresponding plurality of towel retaining rings fastened to said shoes, means connected to the track for securing the shoes and consequently the rings in position to maintain a plurality of clean towels at a predetermined point on the track, and other means connected to the track for locking the shoes to the track, and to permit their withdrawal therefrom when desired.

3. In a towel rack of the character described, a track, a plurality of means slidable in said track, a corresponding plurality of towel retaining rings secured to said means, a cut-out portion on the track for optionally permitting the insertion and removal of said means into and from said track, and a closure member slidably mounted on the track and effective for sealing and unsealing said cut-out portion as desired.

JACQUES ROUSSO.
